UNITED STATES PATENT OFFICE.

JUSTIN BLACHE, OF VALENCE, FRANCE.

POTATO-PEELING MACHINE.

SPECIFICATION forming part of Letters Patent No. 686,576, dated November 12, 1901.

Application filed November 21, 1899. Serial No. 737,764. (No model.)

To all whom it may concern:

Be it known that I, JUSTIN BLACHE, a citizen of the Republic of France, residing at Valence-sur-Rhone, Drôme, in the Republic 5 of France, have invented certain new and useful Improvements in Potato-Peeling Machines, of which the following is a specification.

My invention relates to a new or improved 10 machine for peeling potatoes and other tubers or roots, and has reference to that class of machines wherein the vegetables requiring to be peeled are placed in a kind of barrel, the inner periphery of which is furnished with 15 brushes of special construction, while the movable bottom thereof, which is likewise provided with brushes, receives a rapid rotary motion about a vertical axis, thereby causing the tubers to follow such motion, and 20 in consequence of the centrifugal force thus developed to be constantly thrown against fixed brushes, which divest them of their peel or jacket.

In the accompanying drawings, Figure 1 is 25 a longitudinal elevation, partly in section, showing the driving-shaft carrying the two cranks arranged at one hundred and eighty degrees one relatively to the other. Fig. 2 is a transverse elevation. Fig. 3 is a plan of 30 the machine.

This new or improved potato-peeling machine is arranged in the following manner: The tubers requiring to be peeled are placed in a receiver having the shape of a truncated 35 cone and formed of wooden staves A. The latter are provided up to a given height with brushes made either of bristles, whalebone, or horn. As shown in the plan view of Fig. 40 3, these brushes have a varying length corresponding to the generatrices of the truncated cone. This arrangement has for its object to assist in the decortication of the tubers. The staves are held in position by two 45 cast-iron hoops B B', forming angle-pieces, and by an outer casing of galvanized sheet-iron D, the ends of which are clamped between the hoops B B' and the staves A.

The apparatus is carried by three feet F, cast in one piece and connected together by 50 radial arms f, leading to a boss in the center, carrying a step-bearing G, on which is placed the end or pivot of the vertical shaft J. The

hoops B B' are connected to the three feet F in the following manner—that is to say, the upper hoop B carries on its periphery six 55 bosses, through which pass the iron tie-rods H and I, the lower hoop B' carries upon its periphery three bosses, through which the tie-rods I pass, and the three feet F carry likewise three bosses, through which the tie-rods 60 H pass. The upper hoop is thus connected to the lower hoop B' on the one part and to the three feet F on the other part. The rigidity of the feet relatively to the upper part or frame is secured in all directions by suitable bosses cast some upon the lower hoop B' 65 and some upon the feet F. The upper hoop or open angle-piece B and the lower hoop or closed angle-piece B' close and press the staves one against the other whenever the 70 cross-bolts are tightened up in a similar manner to the hoops of ordinary barrels, so as to form a consolidated whole in the shape of a churn-like tapering vessel, which is thoroughly water-tight. 75

A horizontal driving-shaft U, actuated by means of two crank-handles V, rotates in two bearings cast integrally with a bracket R of suitable shape, which is connected to the hoop by four screws and is provided centrally with a boss, through which passes the vertical shaft J. The horizontal shaft U imparts a rotary motion to the vertical shaft J by the aid of the two bevel-wheels T and S. At the foot of the vertical shaft is keyed a 85 horizontal fly-wheel K, upon which is placed the bottom disk L, furnished with brushes l. The brushes fixed to the periphery of this disk are inclined, as shown in Fig. 1, in order to withstand the action of the centrifugal force 90 and to avoid rubbing when the machine is in motion against the fixed brushes a of the outer casing or receptacle. A cylinder consisting of wooden staves M, provided with brushes m, surrounds the vertical shaft. The lower 95 end of this cylinder, which is provided with a centrally-perforated disk O, bears against the movable bottom disk L, while its upper end is likewise furnished with a centrally-perforated disk N, tightened by two nuts Q. 100 Two other nuts P, arranged under the hub of the fly-wheel, allow of the whole of the movable part being gradually raised as the brushes are wearing. The boss or step-bear-

ing G is furnished with two tiny steel balls g, while the vertical shaft can be properly adjusted by means of a set-screw j, furnished with a tightening-nut j'. A lubricator having a constant level of oil and not shown in the drawings distributes the oil necessary for the lubrication of the machine through a suitable brass pipe.

The tubers requiring to be peeled are wa-
tered at their upper end by a circular per-
forated brass pipe X, which is connected to
any suitable water-supply pipe, such as b.
Below the crown of the fly-wheel is arranged
a zinc gutter Y, designed to receive the water
and the refuse through an opening (not shown
in the drawings) and to convey them to a
suitable receptacle placed below the machine.
A cover-joint or apron Z is nailed on the
staves A. It has for its object to prevent
the water from running between such staves
and the gutter.

A hinged door a' allows of the potatoes or
the like being withdrawn at the end of the
operation. In the machine such as herein-
fore described there is shown a cylinder
formed by wooden staves furnished with
brushes. In smaller-sized machines, how-
ever, such cylinder can be replaced by a cone
of tinned iron.

30 I claim—

1. In a potato-peeling machine, the combi-
nation of a suitably-supported vessel or tub,
provided with brushes on its inner periphery,
an axial shaft in said vessel having suitable
35 means of rotation, a sprayer around the up-

per end of said shaft, a cylindrical sleeve se-
cured on said shaft and provided with cir-
cumferential brushes, a gutter, a fly-wheel
on the lower end of the said shaft the periph-
ery of which wheel turns in said gutter, a 40
cover or apron projecting over the gutter
from the inner wall of the vessel, a disk-
shaped bottom on said fly-wheel, through
which said shaft passes, and upon which said
sleeve rests, said bottom having a number of 45
upwardly-extending brushes, and means for
adjusting and tightening said fly-wheel and
bottom on said shaft, substantially as set
forth.

2. In a potato-peeling machine, the combi- 50
nation of a suitably-supported vessel pro-
vided with brushes on its inner periphery,
said brushes being of alternating varying
lengths, an axial shaft journaled in said
vessel, a disk-shaped bottom fixed on said 55
shaft, and provided with upwardly-extending
brushes, the outermost tufts of which up-
wardly-extending brushes are bodily inclined
inwardly, while the lowermost tufts of the
peripheral brushes on the vessel are bodily 60
inclined upwardly, and means for turning
said shaft, substantially as set forth.

In testimony that I claim the foregoing as
my invention I have signed my name in pres-
ence of two subscribing witnesses.

JUSTIN BLACHE.
